UNITED STATES PATENT OFFICE.

THOMAS W. GARDNER, OF INDIANAPOLIS, INDIANA.

DESIGN FOR A CANE.

SPECIFICATION forming part of Design No. 22,009, dated November 22, 1892.

Application filed October 7, 1892. Serial No. 448,151. Term of patent 3½ years.

To all whom it may concern:

Be it known that I, THOMAS W. GARDNER, a citizen of the United States, residing at Indianapolis, in the county of Marion and State 5 of Indiana, have invented and produced a certain new and original Design for Canes, of which the following is a specification.

The leading feature of my design consists in the representation of a monument formed 10 in relief within a panel, as shown.

In the accompanying drawings, Figure 1 is an elevation of a cane-head embodying my design, in which the portion marked A represents the monument, and B the panel, the

border of which is shown as plain with a 15 rounded top; and Fig. 2 is a side elevation of a cane-head having a crook with my design thereon at the left.

What I claim is—

The design for a cane, substantially as 20 shown.

In witness whereof I have hereunto set my hand and seal at Indianapolis, Indiana, this 4th day of October, A. D. 1892.

THOS. W. GARDNER. [L. S.]

Witnesses:

CHESTER BRADFORD,
JAMES A. WALSH.
